DESIGN FOR A STORAGE BATTERY CASE

Oliver O. Rieser, Oak Park, Ill., assignor to The Richardson Company, Lockland, Ohio, a corporation of Ohio

Application February 6, 1936, Serial No. 61,001

Term of patent 7 years

To all whom it may concern:

Be it known that I, Oliver O. Rieser, a citizen of the United States, residing in Oak Park, in the county of Cook and State of Illinois, have invented a new, original, and ornamental Design for a Storage Battery Case, of which the following is a specification, reference being had to the accompanying drawing, forming part thereof.

In the drawing:—

Figure 1 is a view of the front panel and one end of a storage battery case.

Figure 2 is a view of the rear panel and the other end of a storage battery case.

I claim:

The ornamental design for a storage battery case, as shown.

OLIVER O. RIESER.
